PIPE SMOKER'S DEVICE

Millard A. Rhoads, 1411 Lake Blvd.,
St. Joseph, Mich. 49085
Filed Oct. 9, 1964. Ser. No. 402,721
3 Claims. (Cl. 131—232)

This invention relates to a smoker's device and specifically to improvements in apparatus for conveniently and rapidly cleaning ashes and unburned tobacco from the bowl portion of a smoker's pipe.

The cleaning apparatus comprises an elongate reaming means rotatably connected to the ash receptacle whereby cleaning of the pipe bowl is effected when the bowl is placed over the elongate reaming means and rotated relative to said elongate reaming means. The instant invention employs an improved pipe bowl cleaning apparatus which is located adjacent an ash receptacle. A second embodiment of the apparatus comprises a support means for supporting an ash receptacle and a rotatable elongate reaming means adjacent the ash receptacle.

Therefore, one of the objects of the invention is to provide an ash receptacle means which includes an improved pipe cleaning means.

Another object of the invention is to provide an improved pipe cleaning means adjacent an ash receptacle means.

Still another object of the invention is to provide, in combination, an ash receptacle means and an improved apparatus for cleaning the bowl portion of a smoker's pipe.

A feature of the invention resides in the cleaning apparatus for conveniently and rapidly cleaning ashes and unburned tobacco from the bowl portion of a smoker's pipe.

Another feature of the invention resides in the location of the cleaning apparatus with respect to an ash receptacle, so that ashes and unburned tobacco from the pipe bowl will be deposited into the receptacle during the cleaning operation rather than on furniture, floors or clothes.

Other features and advantages of the invention will be obtained from the following description taken in connection with the accompanying drawings herein in which:

FIGURE 1 is a plan view embodying the invention.

FIGURE 2 is a vertical sectional view taken substantially along line 2—2 of FIGURE 1.

FIGURE 3 is an elevational view taken from the right hand side of FIGURE 1.

FIGURE 4 is a plan view showing a second embodiment of the invention.

FIGURE 5 is a vertical sectional view taken substantially along line 5—5 of FIGURE 4.

In the exemplary embodiment of the invention as disclosed in the drawings, the pipe cleaning apparatus generally designated as 10 is shown to comprise an ash receptacle or tray 11 for receiving ashes and unburned tobacco and a hub portion 12.

Ash receptacle 11 comprises an upwardly opening portion 13 having an annular rim 14. Rim 14 has located thereon a plurality of concave sections 15 for supporting pipes during smoking same. Ash receptacle 11 has a plurality of legs 16 which extend downwardly from portion 13 and support the ash receptacle 11 on such surfaces as table tops (not shown), etc. Legs 16 have apertures 17 that receive rubber tips 18 which substantially eliminates movement of ash receptacle 11 during normal use. A conical support 19 is located near the center of portion 13 and has a top portion 20. Support 19 has a first bore 21 and a second smaller bore 22 which receives hub portion 12.

2

Hub portion 12 comprises a first shaft portion 23 which cooperates with bore 21 and a second shaft portion 24. Shaft portion 24 cooperates with bore 22. Hub portion 12 has an annular shoulder 125 which extends outwardly from shaft portion 23. A nylon washer 26 is located between shoulder 25 and top portion 20 of support 19. The washer 26 serves to provide substantially friction-free movement of hub portion 12 with respect to support 19. A groove 28 is located in shaft portion 23 and a conventional C-washer 29 cooperates with groove 28 to lock hub portion 12 in place.

A cork dome 30 is located in bore 31 of hub portion 12. The cork dome 30 provides the smoker a soft area for tapping the bowl of the smoker's pipe against.

5 An arm member 32 extends outwardly from hub portion 12. A pipe bowl cleaning tool 33 extends upwardly from arm member 32 and is substantially parallel to axis 34 of hub portion 12. When a pipe bowl is placed over tool 33 and a rotational force is applied to the pipe bowl by the smoker, tool 33 is rotated around axis 34. This action causes tool 33 to rotate within and relative to the pipe bowl. The relative movement between the pipe bowl and tool 33 dislodges ashes and unburned tobacco from the pipe bowl in a convenient and rapid manner.

10 Since cleaning tool 33 is located adjacent ash receptacle 11, the receptacle conveniently catches the ashes and unburned tobacco as the cleaning tool 33 dislodges them from the pipe bowl. This design provides for efficient pipe bowl cleaning and simultaneous depositing of ashes and unburned tobacco in an ash receptacle without spilling ashes and unburned tobacco on furniture, rugs and clothing. A tamping tool 35 extends from arm member 32 and is used for packing tobacco in the pipe bowl before the pipe is lit.

15 A second embodiment of the invention is disclosed in FIGURES 4 and 5 of the drawings. Base member 36 supports an ash receptacle or tray 111 and an arm 37 which is located adjacent receptacle 111 and extends above the receptacle. One end of arm 37 is attached to base 36 by suitable means such as screws 38. A cylindrical portion 39 is located at the upper end of arm 37 and has a bore 40 extending longitudinally therethrough.

20 A hub portion 112 has a shaft 41 and an annular shoulder 41a extending outwardly from shaft 41. Shaft 41 and shoulder 41a cooperate with bore 40 and surface 40a to support hub 112 for rotation about centerline 134. A cleaning tool 133 extends from hub portion 112 and has a vertically extending portion 135 which is substantially parallel with axis 134. The cleaning tool 133 is capable of being rotated about axis 134 as described above to clean ashes and unburned tobacco from a pipe bowl. The embodiment of FIGURES 4 and 5 provides for rapid and convenient cleaning of a pipe bowl as well as simultaneous deposit of ashes and unburned tobacco in an ash receptacle. Also, in second embodiment ash receptacle 111 is removable from depressed well 136 in base member 36 for convenient emptying thereof. Well 136 also serves to locate receptacle 111 with respect to cleaning tool 133.

25 Having described my invention as related to the embodiments shown in the accompanying drawing, it is my intention that the invention be not limited by any of the details of description, unless otherwise specified, but rather be construed broadly within its spirit and scope as set out in the accompanying claims.

The embodiment of the invention in which an exclusive property or privilege is claimed is defined as follows:

30 1. An apparatus for cleaning ashes and unburned tobacco from the bowl portion of a smoker's pipe, comprising: receptacle means having upwardly extending side walls for receiving said ashes and unburned tobacco; a

horizontal base member having well means for removably receiving said receptacle means; arm means attached to said base member and extending adjacent and above said receptacle means, said arm means having a hub portion with a vertical bore therethrough positioned above and centrally of said side walls; and elongate means having shaft means positioned in said vertical bore for rotation therein whereby cleaning of said bowl portion is effected upon placing said bowl portion over said elongate means and rotating said elongate means relative to said bowl portion thereby dislodging said ashes and unburned tobacco for direct disposal into said receptacle means.

2. The apparatus of claim 1 wherein said elongate means comprises a conical portion having a longitudinal axis concentric with said bore and a blade portion extending outwardly from said conical portion and upwardly in parallel relation to said axis, said shaft extending downwardly from said conical portion for rotation within said bore.

3. The apparatus of claim 1 wherein a tamping tool extends horizontally, outwardly from said hub portion, said tamping tool length substantially confined within the expanse of said receptacle means side walls.
